St. Louis, Mo.

Application May 13, 1940, Serial No. 334,696

6 Claims. (Cl. 15—147)

This invention relates to floor mops and the like, and has relation to both the mop holder and the mop cloth therefor.

The primary object of the invention is to provide a floor mop holder which is fully protected by a bifurcated mop cloth head against exposure of metal parts thereof.

A further object of the invention is to provide a mop cloth holder which is simple and durable in construction, light in weight, comparatively inexpensive in cost of manufacture, which receives and holds the mop cloth without damage thereto, and which will be simple and convenient to operate when attaching a mop cloth thereto, or removing it therefrom.

A further object of the invention is the provision of a mop cloth holder that will not be likely to get out of order through continued use such, for instance, as the bending or breakage of parts thereof.

A further object of the invention resides in the provision of a mop cloth which includes two rows of yarn mop strands, and a mop head therefor, that can be easily attached to, and detached from, the mop holder and, when attached to the mop holder, serves as a protective covering therefor.

With the above and other objects in view, the invention consists in the various features of construction, arrangement and combination of parts hereinafter more fully described and finally pointed out in the claims hereto appended.

Referring to the accompanying drawings forming a part of this specification, wherein like characters of reference denote similar parts throughout the several views:

Fig. 1 is a front elevation of a mop embodying the features of our invention with parts thereof broken away.

Fig. 2 is an elevation of the mop embodying the features of our invention.

Fig. 3 is an inside plan view of the mop holder flattened out.

Fig. 4 is a top plan view of the mop holder.

Fig. 5 is a plan view showing two groups of spaced mop cloth strands connected by means of a reinforcing head band.

Fig. 6 is a side elevation of Fig. 5.

Fig. 7 is a view showing the mop holder in an inverted position, being applied to the bifurcated head of a mop cloth.

Fig. 8 is a side elevation in full lines of the mop cloth as folded and cut midway the ends of the head band to provide a bifurcated head, 55

and in dotted lines we have shown the branches of the bifurcated head as spread apart.

Referring to the drawings, the mop holder is shown as comprising a pair of sheet metal plates designated 1 and 2. The plates are each cut away at their front edge portions, at spaced intervals, as at 3, and curled, as at 4, to provide a plurality of aligned sleeve-like bearings 5 to receive a suitable hinge pin 6 for connecting the two plates together at the front edges thereof.

The plate members 1 and 2 are each provided midway their rear edges with a rearwardly projecting arm 7. Each arm is longitudinally channeled, and plate members 1 and 2 are dished or 15 depressed outwardly, as at 8, adjacent the base of each arm to correspond to the diameter of the lower end of a mop stick or handle 9. That portion of each plate member 1 and 2 immediately below the inner end of its respective channeled 20 arm 7, is depressed outwardly for forming a continuation of the arm channel and provide a base socket between the plates for the lower end of the mop stick, or handle 9 when the mop holder is secured to the handle. The channeled arms 7 are each provided with a plurality of suitable 25 openings 10.

The mop holder arms 7 are adapted to be secured to the lower end portion of the mop stick, or handle 9 to partially encircle the stick and 30 provide an open sided socket therefor, and the arms are secured to the mop handle 9 by means of a plurality of suitable fastening devices 11, which devices pass through the arm openings 10 and corresponding openings in the mop handle 9.

The rear edge of each plate-like member 1 and 2 is provided with a plurality of inwardly and 35 forwardly projecting V-shaped teeth 12, which provide cooperating jaws for the plate members. The teeth 12 are disposed only on each side of each arm 7 of the mop cloth holder. While we have shown the clamping jaws as formed by V-shaped teeth 12, a plain inwardly and forwardly projecting flange, or rib can be substituted therefor.

The mop holder, when in its closed, or normal position, particularly when secured to the mop handle 9, is substantially V-shaped in formation, and by means of the arms thereof, can be easily attached to and removed from the mop handle 9.

The mop holder structure as above described is adapted to be used in connection with a mop cloth especially designed therefor, and the head of the mop cloth is adapted to serve as a protective covering for the mop holder, as will be apparent hereinafter.

The mop cloth, per se, includes two groups of liquid absorbing yarn strands, or equivalent material, designated 13 and 14. As clearly shown in Figs. 5 and 6, each group of strands 13 and 14 are bound or tied together, in flat formation, at the inner ends thereof, and in spaced relation from each other, by means of a suitable fabric or other similar reinforcing band 15. The band is secured to the strands 13 and 14 of each group by means of a plurality of rows of thread stitchings 16, and opposite sides of the band intermediate the inner ends of each group of strands, and designated 17, are secured together by means of a plurality of rows of thread stitchings 18. The inner bound ends of the strands 13 and 14 provide padded sections 19 and 20, respectively, and will be known hereinafter as branches of a bifurcated mop cloth head 21.

After the mop cloth has been formed, as described, the intermediate section 17 of the band 15 is folded midway its ends to bring the padded mop cloth heads designated 19 and 20 into side by side relation, as shown in Fig. 8. After this has been done, the padded mop cloth heads 19 and 20 are secured together along the inner ends thereof by means of a plurality of rows of thread stitchings 22, as shown in Fig. 8. After this operation, the intermediate section 17 of the band 15 is cut along its fold line, as at 23, and thereby provides the bifurcated mop cloth head 21 with the padded sections 19 and 20 thereof, serving as mop head branches. The non-padded end sections of each branch of the bifurcated mop cloth head after section 17 has been cut, is designated 24. Each branch of the mop cloth head is provided midway its side edges with a suitable opening 25.

To insert the mop holder between the branches of the bifurcated head of the mop cloth, the mop holder is folded into an inverted open position and then the arms 7 of the holder are passed through the openings 25, as shown in Fig. 7. The holder is then moved to its closed position by forcing the hinged edge thereof downwardly so that the plates will lie between the branches 19 and 20 of the bifurcated mop cloth head. After this has been done, the non-padded free end sections 24 of the mop head branches are folded inwardly over the jaw teeth 12 of the plates 1 and 2, and the arms 7 of the mop holder are then secured to the mop stick 9 by means of the fastening devices 11.

This arrangement clamps the non-padded end sections 24 of the mop head branches 19 and 20 between the jaws 12 and the padded branches 19 and 20 of the bifurcated head, as well as the non-padded ends 24 thereof serving to provide an outer protective covering for the plate members 1 and 2 of the mop holder. The arms 7 of the mop holder are secured to the handle 9 after the free ends of the non-padded ends 24 of the branches 19 and 20 have been folded inwardly to be clamped between the jaw teeth 12. The bifurcated mop cloth head is held in position on and as a protective covering for the plate members 1 and 2 of the mop holder by means of the jaw teeth 12, as well as by arms 7 which pass through the openings in the branches of the bifurcated mop head.

It will be apparent from the foregoing description that we have shown and described a mop cloth including a bifurcated head and a hinged mop holder adapted to be disposed between the branches of the bifurcated mop cloth head so that the branches will serve as a protective outer

covering for the mop holder to prevent any part of the plate members 1 and 2 from coming into contact with furniture or other objects in a room while using the mop.

The many advantages of the herein described invention will readily suggest themselves to those skilled in the art to which the invention appertains.

From the foregoing description, it is evident that a simple device for this purpose has been disclosed, but it is to be understood that we do not desire to restrict, or limit ourselves to the very details of the construction shown and described, which is merely illustrative, it being obvious that changes, not involving the exercise of invention, may be made without conflicting or departing from the spirit of the invention within the scope of the appended claims.

What we claim is:

1. A mop including a mop stick having a plurality of openings in its lower end portion, a mop stick head and a mop cloth, said mop stick head consisting of a pair of plates hingedly connected along the front edges thereof, an arm projecting from the rear edge of each plate midway between the side edges thereof, clamping members formed on the rear edge of each plate on opposite sides of the arm projecting therefrom, a mop cloth consisting of two groups of mop yarn strands, a flexible band around the head end of each group of strands, the strands and band of each group being secured together by means of a plurality of rows of thread stitchings, the free end portion of each band projecting beyond the head end of the strands of each group, the banded end of each group of mop yarn strands being stitched together at the inner edge thereof to provide a bifurcated mop cloth head, the banded end of each group of strands having an opening midway its edges through which the plate arms extend outwardly to dispose the hinged plates between the two mop cloth head bands which serve as an outer protective covering for the hinge plates, the free end portions of each head band adapted to be folded inwardly over the outer edges of the hinged plates, said arms adapted to be brought into engagement with the lower end portion of the mop stick, and fastening devices passing through the openings in the arms and the mop stick for detachably locking the mop head to the stick and clamping the mop cloth heads against displacement on the mop stick head.

2. A mop cloth or the like comprising two groups of superimposed mop yarn strands, a flexible fabric band secured to and surrounding each group of strands for a short distance back from the edge of like ends thereof to provide two separable padded head portions, and said head portions being secured together at their inner end portions to provide a mop cloth having a bifurcated head adapted to be attached to a mop head, and each branch of the bifurcated head of the mop cloth having an opening therein midway the side edges thereof.

3. A mop cloth comprising two groups of mop yarn strands, a band stitched to each group of strands to provide a padded head therefor, an edge portion of each band projecting beyond one end of its respective group of strands, the padded heads being united along the inner edge thereof to provide a bifurcated head for the mop cloth, and each branch of the bifurcated head having an opening therein.

4. In a mop structure, a mop stick, a mop stick head and a mop cloth, said mop cloth having a

bifurcated head, each branch of the head having an opening therein, said mop stick head comprising a pair of hinged plates adapted to be disposed between the branches of the mop cloth head, arms projecting from the rear edges of the hinged plates and passing outwardly through the openings in the branches of the mop cloth head, means for detachably securing said arms to the lower end of the mop stick, clamping jaws formed integrally with the rear edge of the hinged plates on opposite sides of said arms, and the free end portions of the branches of the mop cloth head being folded inwardly over the clamping jaws thereby forming a protective outer covering for the plates of the mop stick head by means of each branch of the mop cloth head.

5. In a mop structure, a mop comprising two groups of yarn strands, a band for each group of strands, means for securing the band to the strands to provide each group of strands with a padded head, means for uniting said heads along one edge thereof to provide a bifurcated mop head, each branch of the bifurcated head having an opening therein, a pair of hinged plates adapted to be disposed between the branches of said 25

mop head which branches serve as an outer protective covering for the hinge plates, a pair of arms projecting from the free edges of said plates adapted to pass outwardly through the openings 5 in the branches of said mop head, cooperating jaws formed at the rear edges of said plates on opposite sides of said arms, the free ends of the branches of the mop head adapted to be folded inwardly over the jaws, a mop stick, and means 10 for securing said arms to the mop stick for clamping the free ends of the branches of the mop head between said jaws.

6. A mop holder including a hinged V-shaped head, cooperating jaws on said head, arms projecting therefrom to provide a mop stick receiving socket, a mop cloth including a bifurcated head, the branches of said head lying to the outside of the V-shaped head and serving as a protective covering therefor and the free ends of 15 said branches being folded inwardly and clamped between said jaws when the arms of the mop head are secured to the end of a mop stick.
